UNITED STATES PATENT OFFICE

2,156,393

MACHINE FOR SHAPING UPPERS OVER
LASTS

Bernhardt Jorgensen, Marblehead, Mass., assignor to United Shoe Machinery Corporation, Paterson, N. J., a corporation of New Jersey

Application July 6, 1938, Serial No. 217,795

47 Claims. (Cl. 12—14)

This invention relates to machines for shaping uppers over lasts, and is herein illustrated as applied to a lasting machine of the same general type as disclosed in United States Letters Patent No. 2,075,852, granted on April 6, 1937, upon an application of mine. The invention has more particularly in view the provision of certain improvements in machines of that type, but it is to be understood that in various novel aspects it is not thus limited in its applicability.

The machine shown in the above-mentioned Letters Patent comprises, in a power-operated organization, wipers for wiping the margin of the toe end of an upper inwardly into lasted position over an insole on a last positioned bottom upward, means for wiping the upper about the toe heightwise of the last in response to downward movement imparted to the last before the wipers thus act on the upper, and a device for clamping or gripping the margin of the upper at the end of the toe and to some extent also along the sides of the toe and for pulling the upper heightwise of the last in response to the downward movement of the last. For convenience in inserting the margin of the upper in this device, and to avoid interference with other parts of the machine, the device is arranged to clamp or grip the upper in a location spaced a substantial distance outwardly from the edge of the insole and to maintain the lasting margin in an outspread or outwardly flaring relation to the last and insole during the upper-pulling operation. For greater effectiveness in pulling the upper and in preventing the formation of wrinkles, the device is further arranged to grip the margin of the upper initially at a substantial distance from its edge, in a location substantially opposite the edge of the insole lengthwise and widthwise of the last, the upper being permitted to slip more or less in the device as the pull is applied thereto.

In the use of a machine constructed as above described to last the toe of a shoe in which the margin of the upper immediately beyond the toe-end portion is held in overlaid position on the insole by pulling-over tacks, or in which the margin of the upper has already been fastened in lasted position over the insole from the toe portion rearwardly, the manner in which the margin of the upper is thus held or fastened adjacent to the toe portion prevents the above-mentioned clamping device from engaging and acting effectively on the upper as far along the sides of the toe as would in some cases be desirable for the best results in the shaping of the upper tightly over the last. An object of the

present invention accordingly is to provide improved means for applying a pull to the toe portion of the upper in the lasting operation, so that the pull will in any case be as effective at the sides of the toe as at the end of the toe. 5 For the purposes in view the machine herein shown comprises a device, hereinafter sometimes referred to as an end gripper, constructed substantially as disclosed in the above-mentioned Letters Patent for gripping and pulling the toe 10 end of the upper, except that it does not extend so far around the toe as in the earlier construction but is limited substantially to engagement with the upper at the end of the toe, and grippers separate from this device and arranged to 15 grip and pull the upper in a different manner at the sides of the toe. As illustrated, these side grippers are arranged to grip the margin of the upper in locations nearer its edge than the end gripper and to pull the upper with its margin up- 20 standing, i. e., extending heightwise of the last in substantially perpendicular relation to the shoe bottom, instead of being outspread as at the end of the toe. While the margin of the upper at the end of the toe is permitted to slip in the 25 end gripper as heretofore in the course of the upper-pulling operation, the side grippers which grip the upper nearer its edge are arranged to hold the upper with an unslipping grip, but are so controlled as to permit them to yield in a 30 direction heightwise of the last in response to resistance of the upper to the force of the pull and thus to avoid any danger of an excessive pull.

In the machine shown in the above-mentioned Letters Patent provision is afforded for closing 35 the upper-clamping device on the margin of the upper by depression of a treadle prior to the starting of the power operation of the machine, so that the operator may be sure that the upper is properly clamped before the pull is applied 40 thereto. For purposes of the present invention the construction herein shown is such that both the end gripper and the side grippers are closed prior to the starting of the power operation, the end gripper being first closed by depression of a 45 treadle and the side grippers being thereafter closed by a second depression of the same treadle. To bring about this sequence of operations, novel mechanism is provided for preventing the treadle from acting on the side grippers until after it 50 has been depressed to close the end gripper and has returned to its starting position. It is a further desirable characteristic of the construction herein shown that the side grippers prior to their closing action are moved inwardly widthwise of 55

the shoe from initial retracted positions, such as not to interfere with the mounting of the work in the machine, into upper-gripping positions substantially over the edge of the insole, such 5 inward movements of the grippers as well as their closing movements resulting from depression of the above-mentioned treadle. It has been found that in operating on a shoe in which the upper adjacent to the toe portion is held by 10 pulling-over tacks, or in which the upper has been previously lasted from the toe portion rearwardly, the margin of the upper along the sides of the toe, after the closing of the end gripper, is positioned in such upstanding relation to the shoe 15 bottom that the side grippers ordinarily may be moved inwardly and then immediately closed on the margin by a continuous movement of the treadle without the necessity for any attention on the operator's part to arrangement of the 20 margin between the side gripper jaws.

The means herein shown for pulling the upper at the sides of the toe embody further novel features of the invention, relating especially to gripper-positioning and closing movements and 25 to control of the force of the pull applied to the upper, these features, in certain aspects of the invention, being of general applicability regardless of the number of grippers utilized or of the location or locations where the pull is applied to 30 the upper. With respect to control of the force of the pull, the side grippers herein shown, which are arranged to extend generally widthwise of the last for convenience in presenting and removing the work, are mounted for swinging 35 movements in directions heightwise of the last and are controlled in these movements by levers which are movable similarly to the grippers against the resistance of springs in response to the pull of the upper on the grippers. With respect to the gripper-positioning and closing 40 movements, each side gripper comprises a jaw-carrying member which is movable inwardly from an initial retracted position by the action of a jaw-closing member thereon prior to the 45 closing of the gripper jaws by this member, the inward movement of the jaw-carrying member being thus effected through a spring which is thereafter yieldable to permit the closing of the jaws by further movement of the jaw-closing member. The construction shown further 50 comprises a crank member associated with each side gripper for thus operating its jaw-closing member, a spring through which the jaw-closing member is operated by the crank member, and a 55 device arranged to lock the crank member against reverse movement and thus to maintain the gripper in upper-gripping position with its jaws closed on the upper.

The above and other features of the invention, 60 including various novel details of construction and combinations of parts, will now be more particularly described with reference to the accompanying drawings and thereafter pointed out in the claims.

65 In the drawings.

Fig. 1 is a view in front elevation of the left-hand portion of a machine in which the invention is embodied, with parts broken away;

70 Fig. 2 shows also in front elevation, in greater detail, certain parts that are shown in Fig. 1, with the parts in different positions than in Fig. 1;

Fig. 3 is a plan view of a portion of the structure shown in Fig. 1, with the parts in their initial positions;

75 Fig. 4 shows the same portion of the machine

as Fig. 3, as viewed in elevation from the right of Fig. 1, the parts being shown in their initial positions and the shoe and last being sectioned at the ball portion;

Fig. 5 is a section on the line V—V of Fig. 3; 5

Fig. 6 is a detail view of certain parts in rear elevation;

Fig. 7 shows partly in plan and partly in section a portion of the structure which appears in elevation in the lower portion of Fig. 4; 10

Fig. 8 is a view partly in elevation and partly in section showing one of the side grippers holding the upper under tension; and

Fig. 9 is a vertical sectional view lengthwise of the shoe, illustrating how the margin of the upper is gripped at the end of the toe before the pull is applied. 15

In view of the disclosure in the above-mentioned Letters Patent and the further disclosure of certain details in Letters Patent No. 2,101,069, 20 granted on December 7, 1937, upon an application of mine, only such portions of the complete machine are herein shown as it is necessary to refer to for an understanding of the novel features of this invention, and the construction and 25 operation of such parts as are common to the prior disclosures will be only briefly hereinafter described. The drawings illustrate only the lasting of the toe portion of the shoe, although it will be understood that a machine in which 30 the invention is embodied may also include, for example, heel-end lasting means in accordance with the disclosure of Letters Patent No. 2,075,- 852.

A machine of the illustrated type includes in 35 its organization a heel-end support (not herein shown) which is yieldingly compressible with the last and shoe in the lasting operation, and also a toe rest 2 which supports the forepart of the shoe and is likewise compressible against the 40 resistance of a spring 4. Downward movement of the shoe is effected automatically at the beginning of the power operation of the machine by a toe presser foot 6 (Figs. 1 and 8) arranged to engage the toe end of the insole and a heel presser 45 foot (not shown) which engages the insole at the heel end. The toe presser foot 6 is carried by an arm 8 supported on two aligned posts 10 and 12 which are mounted for vertical movements and for turning movements in bearings 50 in the frame. By means of a handle 14 on the arm 8 the operator swings the arm forwardly to a position in which the toe presser foot 6 is over the toe end of the insole, and as a result of such movement of the arm the machine is started in 55 operation. The posts 10 and 12 are then moved vertically downward to cause the toe presser foot to engage the insole and to depress the toe end of the shoe a certain distance, the heel presser foot operating at the same time to depress 60 the heel end of the shoe. As a result of such depression of the shoe the toe portion of the upper is wiped upwardly by a toe band 16 which embraces the toe end of the shoe. Thereafter the margin of the toe portion of the upper is 65 wiped inwardly over the insole into position to adhere to the insole by a pair of toe-embracing wipers 18 which are advanced lengthwise of the shoe and are closed inward laterally of the shoe. These wipers may, as herein shown, be so extended lengthwise of the shoe as to overlap the margin of the upper somewhat heelwardly of the toe portion of the shoe. After a short dwell of the wipers, which are preferably heated, in pressure-applying relation to the overwiped margin 70 75

of the upper, the parts of the machine are returned to their starting positions. For a better understanding of the construction and operations thus far briefly described the previously mentioned Letters Patent may be consulted.

Similarly also in many respects to the disclosure of Letters Patent No. 2,075,852, the machine herein shown is further provided with means for clamping or gripping the margin of the toe end of the upper prior to the starting of the power operation of the machine, so that in response to the depression of the shoe a pull heightwise of the last is applied to the upper as it is wiped upwardly by the toe band 16. This clamping means, sometimes referred to herein as an end gripper, comprises a lower clamp member 20 positioned over the toe wipers 18 to receive the margin of the upper outspread and another clamp member 22 movable downwardly to clamp the margin of the upper upon the lower clamp member. In the construction herein shown these members are so formed that they are limited substantially to engagement with the upper at the end of the toe instead of extending also along the sides of the toe as in the earlier construction. As illustrated in Fig. 9, the two clamp members are arranged to engage the upper in a location spaced lengthwise of the shoe from the edge of the insole, so that in the upper-pulling operation they maintain the lasting margin of the upper in an outspread or outwardly flaring relation to the last and the insole. The lower clamp member 20 is secured to a bracket 24 which for purposes of adjustment is mounted to turn about a shaft 26 rotatable for a purpose hereinafter described in bearings on a cover plate 28 over the wipers. Screws 30 (Fig. 3) threaded in the bracket 24 rest on the cover plate 28 to determine adjustably the height of the lower clamp member 20. The clamp member 22 is secured to a pair of arms 32 provided with slots 34 through which the shaft 26 extends, these slots being arranged to permit such bodily movements of the arms as to advance the clamp member 22 lengthwise of the shoe from a somewhat retracted initial position as well as to permit swinging movements of the arms to carry the member 22 into upper-clamping position. Mounted for limited swinging movements about pins 36 carried by the arms 32 are blocks 38 provided with pins 40 which are connected by links 42 to crank arms 44 fast on the shaft 26. Springs 46 which in the construction herein shown are mounted in sockets in the arms 32 and engage the blocks 38 tend to swing the blocks in a counterclockwise direction (Fig. 1) about the pins 36 and hold them normally in positions determined by engagement with shoulders (not shown) on the arms. Other springs 48 connected to the pins 40 and to brackets 50 fast on the cover plate 28 tend to move the arms 32 bodily toward the left (Fig. 1) and also to swing them in the direction to lift the clamp member 22, their bodily movements being limited by the shaft 26 and the slots 34 and their swinging movements being limited by their engagement with the cover plate 28. The movement of the clamp member 22 into operative position is effected by turning the shaft 26 in a clockwise direction (Fig. 1). In this operation the crank arms 44 act through the links 42 first to advance the arms 32 bodily as far as permitted by the slots 34 and then to swing them about the axis of the shaft 26 to carry the clamp member 22 into upper-clamping position, the final clamping pressure being applied through the springs 46 in response to swing-

ing movements of the blocks 38 relatively to the arms 32 about the pins 36.

In the construction herein shown the means for turning the shaft 26 for the purpose above described differs somewhat from the disclosure of Letters Patent No. 2,075,852 by reason of its relation to other means provided as hereinafter described for purposes of the present invention. Fast on the front end of the shaft 26 is a crank arm 52 which carries a block 54 provided with a stem 56 (Fig. 3) rotatable in the arm, and extending through a hole in this block is the upper end portion of a rod 58. Between the block 54 and nuts 60 on the rod 58 is a compression spring 62 engaging a washer 64 at its upper end. This spring is normally fully expanded and transmits movement from the rod 58 to the arm 52, the spring being of such strength that ordinarily it does not yield. At its lower end the rod 58 is pivotally connected by a pin 66 to a pawl 68 supported on one arm of a lever 70 which is mounted to swing about a shaft 72, this shaft being mounted in bearings in a bracket 74 secured to a casting 76 (Fig. 4) which, as heretofore, supports the toe band 16 and the wipers 18. Fast in the pawl 68 is a pin 78 by which it is pivotally mounted on a bifurcated portion of the lever 70 (Fig. 7). For a purpose which will hereinafter appear the pawl 68 is provided for turning the shaft 72 in response to swinging movement of the lever 70 in a clockwise direction (Fig. 1), the right-hand end of the pawl being arranged to engage a shoulder 80 formed on a collar 82 which is fastened to the shaft by a set screw 84. A leaf spring 86 fastened on the lever 70 engages the pawl to hold it normally in position thus to act on the shoulder 80. It is not desired, however, to turn the shaft 72 at the time when the end clamp member 22 is moved into upper-clamping position, and accordingly when the lever 70 is swung for this purpose the pawl 68 immediately swings about the axis of the pin 78 against the resistance of the comparatively light spring 86 until its right-hand end is clear of the shoulder 80, by reason of the greater resistance to upward movement of the rod 58 afforded by the springs 48 which control the member 22. Such swinging movement of the pawl is limited by contact of the end portions of the pin 66 with faces 87 (Fig. 7) on the lever 70. It will be understood that the expanded spring 62 is in position to cause the rod 58 to act on the arm 52 without any lost motion, so that the resistance of the springs 48 is effective to cause the swinging of the pawl 68 into position to clear the shoulder 80 at the very beginning of the movement of the lever 70. This lever is operated by a treadle 88 pivoted at 90 on the frame of the machine and compressible against the resistance of a spring 92, the treadle being connected to the lever 70 by a cable 94. A screw 96 threaded in a lug on the bracket 74 serves as a stop in engagement with a lug 98 on the lever 70 to limit the movement of the lever in case, for example, the parts are operated with no shoe in the machine. Return movement of the lever 70 is effected by a torsion spring 100 extending around one of the bearings for the shaft 72 (Fig. 7) with its opposite ends in engagement respectively with the lug 98 on the lever and with an arm 102 (Fig. 1) on the bracket 74. A screw 104 carried by the lever engages the arm 102 to limit such return movement of the lever.

After the end clamp member 22 has been moved to upper-clamping position by depression 76

of the treadle 88 as above described, it is locked in that position by mechanism which differs but little from the disclosure of Letters Patent No. 2,075,852. This mechanism comprises a detent 106 (Figs. 1 and 2) mounted on the previously mentioned stem 56 which is carried by the crank arm 52, the detent having at its lower end a laterally extending finger 108. A spring-pressed plunger 110 mounted in the arm 52 tends 10 to swing the detent about the stem 56 in the direction to carry a screw 112 which is threaded therein into engagement with a lug 114 on the arm 52. When the arm 52 is in its initial position, however, as shown in Fig. 1, the detent 106 15 is held in a position in which the screw 112 is spaced from the lug 114 by reason of engagement of the detent with a lug 116 formed on a plate 118 which is fast on one end of a shaft 120 (Figs. 1 and 3), this being a shaft which by turning 20 movement in a clockwise direction (Fig. 1) imparts, as heretofore, to the wipers 18 their operative movements. When the crank arm 52 is swung upwardly by depression of the treadle 88 to move the clamp member 22 into upper- 25 clamping position the detent 106 is raised until its laterally extending finger 108 clears the lug 116, whereupon the plunger 110 swings the detent into the position in which it is shown in Fig. 2. It will thus be seen that the lug 116 by 30 engagement with the finger 108 serves to hold the clamp member 22 in upper-clamping position. When in the course of the operation of the machine the shaft 120 is turned to operate the wipers the lug 116 is carried out from under 35 the finger 108, thus permitting the clamp member to be returned to its initial position by the springs 48. The arrangement of the parts is such that the clamp member is thus released substantially at the time when the wipers begin 40 to wipe the margin of the upper inwardly over the insole. In the construction herein shown there is further provided means whereby the operator may, if he wishes, conveniently cause the clamp member 22 to return to its initial position before he starts the power operation of the 45 machine in case the upper has not been properly clamped. This means comprises a lever 122 pivotally mounted at its lower end on a plate 124 which is fastened on the casting 76, this lever 50 being provided with a pin 126 for engaging the detent 106 and swinging its finger 108 from over the lug 116 to release the arm 52.

The machine is further provided, for purposes of this invention, with side grippers 128 arranged 55 to grip the margin of the upper at the sides of the toe and to pull the upper heightwise of the last simultaneously with the end gripper as the shoe is depressed within the toe band 16. The gripper which thus acts on the upper at the side 60 of the shoe which is toward the front of the machine will be sometimes referred to herein-after as the front gripper and the other one as the rear gripper. These two grippers and the mechanisms for operating and controlling them 65 are, for the most part, substantially alike. Each gripper comprises a jaw-carrying member or bar 130 extending substantially horizontally over the cover plate 28 in a direction widthwise of the shoe and provided at its inner end with a pair 70 of upper-gripping jaws 132 and 134 (Fig. 5). The jaw 132 is detachably secured in fixed relation to the bar 130 by a pin 136 on which the jaw 134 is mounted to swing. The jaws are intended to hold the upper with an unslipping grip, the jaw 132 being provided for this purpose

with a projection 138 located opposite a recess 140 in the other jaw. Pivotally connected at its inner end to the jaw 134 is a jaw-closing rod 142 the outer end portion of which extends through a trunnion block 144 provided with pins 146 rotatably mounted in a pair of crank members 148. 5 These crank members are spaced from each other to receive the trunnion block between them and are keyed to a rockshaft 150 mounted in a bracket 152 which is secured to the cover plate 28. In 10 response to turning movement of the shaft 150 the two crank members 148 act as a unit to impart through the trunnion block 144 inward movement to the jaw-closing rod 142, the construction being such that by this movement of 15 the rod the bar 130 is first moved inwardly to carry the open gripper jaws widthwise of the shoe from an initial retracted position, such as to facilitate the mounting of the shoe in the machine, to upper-gripping position substantially 20 over the edge of the insole. For this purpose there are provided two springs 154 and 156 through which the rod 142 extends and each of which abuts at one end against a collar 158 threaded on the rod. The other end of the spring 25 154 abuts against one end of the trunnion block 144 which is confined on the rod by nuts 160. The other end of the spring 156 abuts against a thimble 162 slidingly mounted on the rod 142 and engaging a shoulder 164 on the bar 130. It 30 will thus be seen that the trunnion block 144 acts on the rod 142 through the spring 154 and that the rod acts on the bar 130 through the spring 156. Through both springs, therefore, the bar 130 is first moved inwardly, after which the 35 spring 156 yields to permit the rod 142 to move relatively to the bar 130 and thus to impart upper-gripping movement to the jaw 134 in response to continued movement of the crank members 148. After the upper has been gripped the 40 spring 154 may yield in response to further movement of the trunnion block 144, the upper therefore being held by the jaws through the force 45 of this spring.

For supporting the bar 130 and guiding it in its movements, there are provided two pins 166 and 168 on which the bar rests near its inner and outer ends, respectively. The pin 168 is mounted in the bracket 152 and extends through a slot 170 in the bar, so that it prevents any upward 50 movement of the outer end portion of the bar and serves as a fulcrum about which the bar may swing in directions heightwise of the shoe, and threaded in the outer end of the bar is a screw 172 which by engagement with the pin 168 55 limits adjustably the inward movement of the bar to determine the upper-gripping position of the gripper jaws laterally of the shoe. It will be understood that it is after the inward movement of the bar has been stopped by the pin 168 60 that the rod 142 moves relatively to the bar to cause the jaws to grip the upper. The pin 166 which underlies the inner end portion of the bar 130 is carried by the inner end of a lever 174 mounted to swing heightwise of the shoe on a 65 pin 176 which is supported in a member fast on the cover plate 28. Connected to the outer end of this lever is a spring 178 controlled as herein-after described, this spring tending to swing the inner end of the lever upwardly. A screw 180 70 threaded in the lever 174 and engaging the top of the cover plate 28 limits adjustably such swinging movement of the lever and accordingly determines the normal height of the gripper jaws. As the shoe is depressed the spring 178 75

may yield in response to the pull of the upper on the gripper jaws, thus avoiding any danger of damaging an upper by subjecting it to excessive tension. To permit such swinging movement of the lever 174 against the resistance of the spring 178 the cover plate 28 is provided with a recess 182 located under the pin 166 and the inner end of the lever. Fast on the top of the inner end portion of the lever is a plate 184 arranged to overlap a portion of the bar 130 to prevent any uncontrolled upward swinging movement of the gripper jaws under the influence of the spring 178 when they release the upper. The bar 130 is further guided in its movements by engagement of one side thereof with the lever 174 and by the engagement of its opposite side with a member 186 fast on the cover plate 28.

Each of the springs 178 is connected at its lower end to a crank arm 188 fast on one end 20 of a shaft 190 mounted in bearings in the bracket 152. Fast on the other end of each shaft 190 is a crank member 192 by which the shaft may be turned to vary the tension of the spring 178. These two crank members are connected together by a flexible cable 194 (Fig. 4) and are provided with segmental portions having grooves 196 therein to receive this cable. The crank member 192 at the front of the machine is provided with a spring-pressed pin 198 (Fig. 1) arranged to enter any one of a plurality of holes 200 (Fig. 4) provided in a segmental portion of a bracket 202 secured to the front bracket 152. A knob 204 on the pin 198 serves as means whereby the pin may be withdrawn from any one of the holes 200 and also as means for swinging the front crank member 192. It will be understood that the rear crank member swings in unison with the front member, and accordingly the tensions of the two springs 178 are simultaneously varied equal amounts to vary the forces with which the respective grippers will pull the upper. Since both springs 178 are always under tension, the rear spring serves to keep the cable 194 taut at all times.

For operating the crank members 148 to move the grippers inwardly and to cause them to grip the upper, there is fast on each of the rock shafts 150 a crank arm 206 (Figs. 3 and 4). The arm 206 at the front of the machine is connected by a flexible cable 208 to a crank arm 210 (Fig. 7) fast on the previously mentioned shaft 12, the arm 210 carrying a screw 212 arranged to engage the bracket 74 to prevent the arm from being swung too far upwardly. The rear crank arm 206 is connected by a cable 214 to an arm 216 which is pivotally mounted on a pin 218 carried by another arm 220 fast on the shaft 12. A screw 222 carried by the arm 216 is arranged to engage the arm 220 (Fig. 1) to determine adjustably the position of the arm 216 relatively to the arm 220. It will be understood that operative downward movements of the crank arms 206 result from the turning of the shaft 12 in a clockwise direction (Fig. 1) in response to depression of the treadle 88, through engagement of the pawl 88 with the shoulder 80 on the member 82 which is fast on the shaft as hereinbefore described. As previously explained, the pawl is inoperative thus to turn the shaft at the time 65 when the treadle 88 is depressed to move the end clamp member 22 into upper-clamping position, and accordingly the clamping of the end of the upper occurs while the side grippers are open and in their retracted positions. When 70 the treadle is next depressed, however, the pawl

68 remains in position to act on the member 82, since the crank arm 52 is locked in such an elevated position that there is no resistance to the upward movement of the rod 56 such as would cause the pawl to swing against the resistance of the spring 86. 5

For maintaining the side grippers normally in their initial retracted positions, each pair of crank members 148 is controlled by a spring 224 (Figs. 4 and 5), the upper end of the spring being 10 connected to a pin 226 (Fig. 1) which extends between the two crank members and its lower end being connected to a pin 228 carried by a latch 230 which is mounted to swing about the shaft 190. The spring thus tends both to swing the crank members in the direction to retract the gripper and also to hold the latch 230 against the curved periphery of a segmental portion of one of the crank members, as illustrated in Fig. 5. The initial position of the gripper is determined 20 by engagement of the ends of the pin 226 with lugs 231 on the bracket 152. The crank member 148 engaged by the latch is provided with a notch 232 which receives the latch when the two crank members have been swung far enough to cause 25 the gripper to grip the upper. Accordingly the two grippers are locked by the respective latches in upper-gripping positions with their jaws closed when the operator releases the treadle 88. Fastened to each latch is a handle 234 for swinging 30 it out of the notch 232, so that if the upper is not properly gripped the operator may cause the grippers to open and return to their initial positions. It will be understood that the springs 224 effect such return movements of the grippers, the 35 trunnion blocks 144 acting on the nuts 160 to move the rods 142 outwardly and these rods imparting outward movements to the bars 130 by reason of engagement of the open jaws 134 with shoulders 235 on the bars. In this operation the 40 two cables 208 and 214 are moved upwardly by the two crank arms 206 to return the arms 210 and 216 to their starting positions. There is further provided means for operating the latches 230 automatically to cause the side grippers to 45 release the upper at substantially the same time in the power operation of the machine when the end gripper releases the upper, that is, substantially at the time when the wipers begin to wipe the margin of the upper inwardly over the 50 insole. The means for thus operating the latch which controls the front gripper comprises a bell-crank lever 236 (Fig. 1) mounted on the bracket 152, one arm of this lever carrying a screw 238 the upper end of which is under the 55 tail portion of the latch 230 (Fig. 5) for retracting the latch when this arm swings upwardly. For operating this bell-crank lever its other arm is connected by a link 240 (Fig. 1) to the previously mentioned plate 118 which is fast on the 60 front end of the wiper-operating shaft 120. Accordingly, when this shaft is turned in the direction to operate the wipers operative movement is imparted to the bell-crank lever 236 substantially at the time when the lug 116 on the 65 plate 118 releases the crank arm 52 which controls the end clamp member 22. For similarly operating the latch 230 which controls the rear gripper, a bell-crank lever 242 (Figs. 4 and 6) mounted on the rear bracket 152 carries a screw 70 244 which underlies a tail on the latch, this bell-crank lever being connected by a link 246 to a crank arm 248 fast on the rear end of the shaft 120.

In the use of the machine the operator mounts 75

a shoe and its last bottom upward on the heel-end support and on the toe rest 2. Such a shoe, as herein illustrated, may be one which has been previously lasted from the toe portion rearwardly, at least along the ball and shank portions, and may also have pulling-over tacks located immediately at the rear of the toe portion and clinched on the usual last bottom plate. When the shoe is thus presented its toe end is held by the toe rest 2 at such an elevation that the edge of the insole is higher than the toe band 16 and the edges of the wipers 18; and the lower clamp member 20 of the end gripper, positioned immediately above and close to the wipers, is arranged to engage the margin of the upper outspread in a location at substantially the same height as the edge of the insole and spaced lengthwise of the insole from the edge of the latter. After arranging the margin of the end of the upper in proper position over this clamp member, the operator depresses the treadle 88 to move the cooperating clamp member 22 into upper-clamping position, this member being locked in that position by engagement of the lug 116 with the detent finger 108. As previously explained, this depression of the treadle does not impart any turning movement to the shaft 72 and therefore has no effect on the side grippers. If the operator should now observe that the margin of the end of the upper is not properly clamped, he may, by use of the lever 122, swing the detent finger 108 in such manner as to release the end clamp member 22. In that case he will proceed to rearrange the margin of the end of the upper and will then cause it again to be clamped by another depression of the treadle.

With the margin of the upper clamped at the end of the toe as above described, its opposite side margins extending from the end gripper to the pulling-over tacks are positioned generally in upstanding relation to the shoe bottom, and the jaws of the opposite side grippers are so arranged that when they have been moved inwardly into upper-gripping positions substantially over the edge of the insole the margins of the upper thus positioned will ordinarily be located between the jaws ready to be gripped when the jaws are closed. The jaws of these grippers are arranged to engage the upper in locations somewhat higher than the end gripper, in view of the upstanding positions of the side margins of the upper. By another depression of the treadle 88 the operator moves the side grippers from their initial retracted positions into their upper-gripping positions determined by engagement of the stop screws 172 with the pins 168 and closes the jaws on the upper by continued movement of the treadle, the latch members 230 entering the notches 232 of the crank members 148 to lock the grippers in their inner positions with the jaws closed. If the operator should observe that the margin of the upper is not properly gripped by the side grippers, he may cause them to open and return to their starting positions by use of the handles 234 to withdraw the latches 230 from the notches 232. He will then move the grippers inwardly again by the treadle, taking care to insure that the upper is properly positioned between the gripper jaws before the treadle is moved far enough to close the jaws.

After the upper has been gripped at the end and the sides of the toe as above described, the operator starts the power operation of the ma-

chine by swinging the arm 8 forwardly, and as the machine starts to operate the shoe is depressed by the toe presser foot 6 and the co-operating heel presser foot, causing the toe band 16 to wipe the upper upwardly toward the edge 5 of the insole. In this operation the upper is pulled heightwise of the last by the end and side grippers, the upper slipping more or less in the end gripper as the pull is applied, but being held with an unsliping grip by the side grippers, since 10 these grippers grip the upper nearer its edge than the end gripper. These side grippers, however, are yieldingly movable against the resistance of the springs 178 in response to the pull of the upper on the gripper jaws, so that insurance 15 is afforded against an excessive pull, the springs being adjustable to vary the force of the pull. By reference to Fig. 8 it will be seen that in the upper-pulling operation the lasting margin of the upper is maintained by the side grippers in 20 substantially perpendicular relation to the shoe bottom and substantially in contact with the edge of the insole. After the depression of the shoe the toe wipers are advanced and closed to wipe the margin of the upper inwardly over the 25 insole, the end and side grippers being released automatically to permit them to open and return to their starting positions substantially at the time when the wipers begin to wipe the upper over the edge of the insole. After the upper 30 has been subjected to the pressure of the wipers a predetermined length of time, so that it adheres firmly to the insole by reason of the presence of cement previously applied, the wipers are retracted and the shoe is released to permit it to 35 be removed from the machine.

Having described the invention, what I claim as new and desire to secure by Letters Patent of the United States is:

1. In a machine for shaping uppers over lasts, 40 a device for embracing an upper about the toe end of a last and for wiping the upper heightwise of the last, means for effecting relative movement of said device and the last to cause the device thus to act on the upper, means for pulling 45 the upper heightwise of the last at the end and the sides of the toe in the course of said relative movement, said upper-pulling means being arranged to maintain the lasting margin of the upper outspread at the end of the toe and in substantially perpendicular relation to the shoe bottom at the sides of the toe in the upper-pulling operation, and means for wiping the margin of the upper about the toe inwardly over the bottom of the last into lasted position after the pulling 50 of the upper.

2. In a machine for shaping uppers over lasts, 60 a device for embracing an upper about the toe end of a last having an insole thereon and for wiping the upper heightwise of the last, means for moving the last heightwise relatively to said device to cause the device thus to act on the upper, an end gripper and side grippers for pulling the upper respectively at the end and the sides of the toe in response to such movement of the last, 65 the end gripper being arranged to maintain the lasting margin of the upper outspread by engaging it in a location spaced lengthwise of the last from the edge of the insole, the side grippers being arranged to maintain the lasting margin in generally upstanding relation to the shoe bottom by engaging it in locations spaced substantially the same distance apart as the opposite side edges of the toe end of the insole, and means for wiping the margin of the upper about the 70 75

toe inwardly over the insole into lasted position after the pulling of the upper by the grippers.

3. In a machine for shaping uppers over lasts, a device for embracing an upper about the toe 5 end of a last and for wiping the upper heightwise of the last, means for effecting relative movement of said device and the last to cause the device thus to act on the upper, an end gripper and side grippers for pulling the upper respectively at the 10 end and the sides of the toe in the course of said relative movement, the end gripper being arranged to maintain the lasting margin of the upper outspread while permitting the upper to slip therein in the upper-pulling operation, the side 15 grippers being arranged to maintain the lasting margin in generally upstanding relation to the shoe bottom while holding it with an unslipping grip as the pull is applied, spring means against the resistance of which the side grippers are yieldable heightwise of the last in response to resistance of the upper to the force of the pull, and means for wiping the margin of the upper about the toe inwardly over the bottom of the last into 20 lasted position after the pulling of the upper by 25 the grippers.

4. In a machine for shaping uppers over lasts, a device for embracing an upper about the toe end of a last having an insole thereon and for wiping the upper heightwise of the last, means 30 for moving the last heightwise relatively to said device to cause the device thus to act on the upper, an end gripper and side grippers for pulling the upper respectively at the end and the sides of the toe in response to such movement of the 35 last, the end gripper being arranged to maintain the lasting margin of the upper outspread by engaging it in a location spaced lengthwise of the last from the edge of the insole while permitting the upper to slip therein in the upper-pulling 40 operation, the side grippers being arranged to grip the upper initially in locations spaced substantially the same distance apart as the opposite side edges of the toe end of the insole and to hold the lasting margin in generally upstanding relation to the shoe bottom while maintaining an 45 unslipping grip thereon as the pull is applied, spring means against the resistance of which the side grippers are movable heightwise of the last in response to resistance of the upper to the force of the pull, and means for wiping the margin of the upper 50 about the toe inwardly over the insole into lasted position after the pulling of the upper by the grippers.

5. In a machine for shaping uppers over lasts, 55 a device for embracing an upper about the toe end of a last positioned bottom upward and having an insole thereon and for wiping the upper heightwise of the last, means for depressing the last to cause said device thus to act on the upper, 60 an end gripper and side grippers for pulling the upper respectively at the end and the sides of the toe in response to the depression of the last, the end gripper being arranged to engage the margin of the upper initially in a location spaced lengthwise of the last from the edge of the insole and to hold the upper with an unslipping grip as the pull is applied, spring means against the resistance of which the side grippers are movable in response to 65 resistance of the upper to the force of the pull, and means for wiping the margin of the upper about the toe inwardly over the insole into lasted position after the pulling of the upper by the grippers.

6. In a machine for shaping uppers over lasts, 70 75 a device for embracing an upper about the toe

end of a last positioned bottom upward and having an insole thereon and for wiping the upper heightwise of the last, means for depressing the last to cause said device thus to act on the upper, an end gripper and side grippers for pulling the 5 upper respectively at the end and the sides of the toe in response to the depression of the last, the end gripper being arranged to maintain the lasting margin of the upper outspread while permitting the upper to slip therein in the upper-pulling operation, the side grippers being arranged to engage the margin of the upper in locations higher than the end gripper and to hold it with an unslipping grip as the pull is applied, spring means against the resistance of which the 10 side grippers are movable heightwise of the last in response to resistance of the upper to the force of the pull, and means for wiping the margin of the upper about the toe inwardly over the insole into lasted position after the pulling of the upper 15 by the grippers.

7. In a machine for shaping uppers over lasts, an end gripper and side grippers for pulling an upper over the toe of a last at the end and the sides of the toe respectively, means for effecting 20 relative movement of said grippers and the last in a direction heightwise of the last to cause the grippers to pull the upper, the end gripper being arranged to maintain the lasting margin of the upper outspread while permitting the upper to 25 slip therein in the upper-pulling operation, the side grippers being arranged to maintain the lasting margin in substantially perpendicular relation to the shoe bottom while holding it with an unslipping grip as the pull is applied, spring means 30 against the resistance of which the side grippers are yieldable heightwise of the last in response to resistance of the upper to the force of the pull, and means for wiping the margin of the upper about the toe inwardly over the bottom of the last 35 into lasted position after the pulling of the upper 40 by the grippers.

8. In a machine for shaping uppers over lasts, an end gripper and side grippers for pulling an upper over the toe of a last positioned bottom 45 upward with an insole thereon by engagement with the upper at the end and the sides of the toe respectively, means for depressing the last to cause the grippers thus to pull the upper, the end gripper being arranged to maintain the lasting 50 margin of the upper outspread by engaging it in a location spaced lengthwise of the last from the edge of the insole and to permit the upper to slip therein in the upper-pulling operation, the side grippers being arranged to maintain the lasting 55 margin of the upper in generally upstanding relation to the shoe bottom by engaging it in locations substantially over the edge of the insole and to hold the upper with an unslipping grip as the pull is applied, spring means against the resistance of which the side grippers are movable in response to 60 resistance of the upper to the force of the pull, and means for wiping the margin of the upper about the toe inwardly over the insole into lasted position after the pulling of the upper by the grippers. 65

9. In a machine for shaping uppers over lasts, the combination with wipers for wiping the margin of the toe end of an upper inwardly over an insole on a last, of means for pulling the upper heightwise of the last at the end and the sides of 70 the toe before its margin is wiped inwardly by said wipers, said upper-pulling means being arranged to clamp the margin of the upper outspread over the wipers at the end of the toe only and to hold the margin in upstanding relation to the shoe 75

- bottom substantially in contact with the edge of the insole at the sides of the toe in the upper-pulling operation.
10. In a machine for shaping uppers over lasts, 5 the combination with wipers for wiping the margin of the toe end of an upper inwardly over an insole on a last positioned bottom upward, of an end gripper and side grippers for pulling the upper heightwise of the last at the end and the sides of the toe respectively, the end gripper comprising a member positioned over said wipers and another member movable heightwise of the last toward the wipers to clamp the margin of the upper outspread against said first-named member, the side 10 grippers being arranged to engage the upper initially in locations higher than said end gripper and substantially over the edge of the insole, and means for effecting relative movement of said grippers and the last in a direction heightwise of the last to cause the grippers to pull the upper before its margin is wiped inwardly by the wipers.
11. In a power-operated machine for shaping uppers over lasts, an end gripper and side grippers for pulling an upper over the toe of a last at the 15 end and the sides of the toe respectively, means for effecting relative movement of said grippers and the last in a direction heightwise of the last to cause the grippers to pull the upper in the power operation of the machine, the end gripper being arranged to maintain the lasting margin of the upper outspread and the side grippers to maintain it in generally upstanding relation to the shoe bottom in the upper-pulling operation, means to cause all said grippers to grip the upper 20 prior to the starting of the power operation of the machine, and means for wiping the margin of the upper about the toe inwardly over the bottom of the last into lasted position after the pulling of the upper by the grippers.
12. In a power-operated machine for shaping uppers over lasts, a device for embracing an upper about the toe end of a last and for wiping the upper heightwise of the last, means for effecting relative movement of said device and the last to cause the device thus to act on the upper in the power operation of the machine, grippers arranged to grip the margin of the upper respectively at the end and the sides of the toe and to pull the upper heightwise of the last in the course of said relative movement, means to cause said grippers to grip the upper prior to the starting of the power operation of the machine, wipers for embracing the toe end of the upper and for wiping its margin inwardly over the bottom of the last into lasted position, and automatic means to cause said grippers to release the upper to permit its margin to be wiped inwardly by the wipers.
13. In a power-operated machine for shaping uppers over lasts, a device for embracing an upper 40 about the toe end of a last and for wiping the upper heightwise of the last, means for effecting relative movement of said device and the last to cause the device thus to act on the upper in the power operation of the machine, grippers arranged to grip the margin of the upper respectively at the end and the sides of the toe and to pull the upper heightwise of the last in the course of said relative movement, means movable by the operator to close the end and side grippers on the upper prior to the starting of the power operation of the machine, locking devices associated respectively with the different grippers for holding them closed on the upper, wipers for embracing the toe end of the upper and for wiping its margin in- 45
- wardly over the bottom of the last into lasted position, and automatic means for operating said locking devices to release the grippers and permit them to open in time relation to the operation of the wipers.
14. In a power-operated machine for shaping uppers over lasts, a device for embracing an upper about the toe end of a last and for wiping the upper heightwise of the last, means for effecting relative movement of said device and the last to cause the device thus to act on the upper in the power operation of the machine, grippers arranged to grip the margin of the upper respectively at the end and the sides of the toe and to pull the upper heightwise of the last in the course of said relative movement, means for moving the side grippers widthwise of the last from retracted positions into upper-gripping positions and for closing the end and side grippers on the upper prior to the starting of the power operation of the machine, wipers for embracing the toe end of the upper and for wiping its margin inwardly over the bottom of the last into lasted position, and automatic means to cause said grippers to release the upper in time relation to the operation of the wipers.
15. In a power-operated machine for shaping uppers over lasts, grippers arranged to grip the margin of an upper on a last at the end and the sides of the forepart respectively, means for effecting relative movement of said grippers and the last to cause the grippers to pull the upper in the power operation of the machine, and means comprising a member common to all said grippers for moving the side grippers from retracted positions into upper-gripping positions and for closing the end and side grippers on the upper prior to the starting of the power operation of the machine.
16. In a power-operated machine for shaping uppers over lasts, grippers arranged to grip the margin of an upper on a last at the end and the sides of the forepart respectively, means for effecting relative movement of said grippers and the last to cause the grippers to pull the upper in the power operation of the machine, and means comprising a member common to all said grippers and movable by the operator first to cause the end gripper to grip the upper and then to move the side grippers from retracted positions into upper-gripping positions and to cause them also to grip the upper prior to the starting of the power operation of the machine.
17. In a power-operated machine for shaping uppers over lasts, grippers arranged to grip the margin of an upper on a last at the end and the sides of the forepart respectively, means for effecting relative movement of said grippers and the last to cause the grippers to pull the upper in the power operation of the machine, a gripper-controlling member movable by the operator, means to cause the end gripper to grip the upper in response to one movement of said member, and means to cause the side grippers thereafter to grip the upper in response to another movement of said member prior to the starting of the power operation of the machine.
18. In a power-operated machine for shaping uppers over lasts, grippers arranged to grip the margin of an upper on a last at the end and the sides of the forepart respectively, means for effecting relative movement of said grippers and the last to cause the grippers to pull the upper in the power operation of the machine, the side grippers being mounted for movements in di- 70
- 75
- 76

rections widthwise of the last from initial retracted positions into upper-gripping positions, a gripper-controlling member movable by the operator, means for closing the end gripper on the upper in response to one movement of said member, and means for moving the side grippers from their retracted positions to their upper-gripping positions and for closing them on the upper in response to another movement of said member prior to the starting of the power operation of the machine.

19. In a power-operated machine for shaping uppers over lasts, grippers arranged to grip the margin of an upper on a last at the end and the sides of the forepart respectively, means for effecting relative movement of said grippers and the last to cause the grippers to pull the upper in the power operation of the machine, means movable by the operator to close the end gripper and the side grippers on the upper prior to the starting of the power operation of the machine, gripper-opening springs against the resistance of which said means is effective thus to close the grippers, locking devices for holding the grippers closed, and automatic means for operating said locking devices in the power operation of the machine to release the grippers and permit them to open.

20. In a power-operated machine for shaping uppers over lasts, grippers arranged to grip the margin of an upper on a last at the end and the sides of the forepart respectively, means for effecting relative movement of said grippers and the last to cause the grippers to pull the upper in the power operation of the machine, means for moving the side grippers in directions widthwise of the last from retracted positions into upper-gripping positions and for closing the end and side grippers on the upper prior to the starting of the power operation of the machine, springs tending to open the grippers and to return the side grippers to their starting positions, devices for holding the grippers closed and the side grippers in their upper-gripping positions against the resistance of said springs, and automatic means for operating said devices in the power operation of the machine to release the grippers to the action of said springs.

21. In a power-operated machine for shaping uppers over lasts, grippers arranged to grip the margin of an upper on a last at the end and the sides of the forepart respectively, means for effecting relative movement of said grippers and the last to cause the grippers to pull the upper in the power operation of the machine, means movable by the operator to close the end gripper and the side grippers on the upper prior to the starting of the power operation of the machine, springs tending to open said grippers, devices associated respectively with the different grippers for holding them closed, automatic means for operating said devices in the power operation of the machine to release the grippers to the action of said springs, and means to enable the operator to operate any one of said devices separately to release the gripper associated therewith prior to the starting of the machine.

22. In a machine for shaping uppers over lasts, an end gripper and side grippers arranged to grip the margin of an upper on a last at the end and the sides of the forepart respectively, a gripper-controlling member movable by the operator, means for closing the end gripper on the upper in response to one movement of said member, means for closing the side grippers on the upper

in response to another movement of said member, and means for effecting relative movement of said grippers and the last to cause the grippers to pull the upper only after all the grippers have thus been closed.

23. In a machine for shaping uppers over lasts, an end gripper and side grippers arranged to grip the margin of an upper on a last at the end and the sides of the forepart respectively, a gripper-controlling member movable by the operator, means for closing the end gripper on the upper in response to one movement of said member, means for moving the side grippers from retracted positions into upper-gripping positions and for then closing them on the upper in response to another movement of said member, and means for effecting relative movement of said grippers and the last to cause the grippers to pull the upper only after all the grippers have thus been closed.

24. In a machine for shaping uppers over lasts, an end gripper and side grippers arranged to grip the margin of an upper on a last at the end and the sides of the forepart respectively, and means comprising a member movable by the operator and common to all said grippers for moving the side grippers from retracted positions into upper-gripping positions and for closing the end and side grippers on the upper prior to the pulling of the upper by any of the grippers.

25. In a machine for shaping uppers over lasts, an end gripper and side grippers arranged to grip the margin of an upper on a last at the end and the sides of the forepart respectively, gripper-closing mechanisms associated respectively with said end and side grippers for closing them to grip the upper, a member common to said different mechanisms and movable to cause them to close the grippers, and means operative in response to resistance of the end-gripper-closing mechanism to the movement of said member to prevent the member from operating on the side-gripper-closing mechanisms until after the end gripper has been closed.

26. In a machine for shaping uppers over lasts, an end gripper and side grippers arranged to grip the margin of an upper on a last at the end and the sides of the forepart respectively, gripper-closing mechanisms associated respectively with said end and side grippers for closing them to grip the upper, a member common to said different mechanisms and movable to cause them to close the grippers, and a device for transmitting movement from said member to the side-gripper-closing mechanisms, said device comprising parts relatively displaceable in response to resistance of the end-gripper-closing mechanism to the movement of said member to prevent the member from acting on the side-gripper-closing mechanisms until after the end gripper has been closed and the member has been returned toward starting position.

27. In a machine for shaping uppers over lasts, an end gripper and side grippers arranged to grip the margin of an upper on a last at the end and the sides of the forepart respectively, gripper-closing mechanisms associated respectively with said end and side grippers for closing them to grip the upper, a member common to said different mechanisms and movable to cause them to close the grippers, a shaft rotatable by said member to operate the side-gripper-closing mechanisms, and a pawl for rotating said shaft by movement of said member, said pawl being

displaceable from operative position in response to resistance of the end-gripper-closing mechanism to the movement of said member to prevent rotation of the shaft until after the end gripper 5 has been closed and the member has been returned toward starting position.

28. In a machine for shaping uppers over lasts, an end gripper and side grippers arranged to grip the margin of an upper on a last at the end and 10 the sides of the forepart respectively, gripper-closing mechanisms associated respectively with said end and side grippers for closing them to grip the upper, a lever common to said different mechanisms and movable to cause them to close 15 the grippers, a member movable by said lever to operate the side-gripper-closing mechanisms, a pawl pivotally mounted between its ends on said lever for operating said member by the movement of the lever, a spring for normally holding said 20 pawl with one end thereof in operative relation to said member, and a connection between the other end of said pawl and the end-gripper-closing mechanism for displacing said pawl from operative position in response to resistance of said 25 last-named mechanism to the movement of the lever and for thus preventing operation of said member by the pawl until the end gripper has been closed and the lever is again operated after its return toward starting position.

30. 29. In a machine for shaping uppers over lasts, grippers arranged respectively to grip different portions of the margin of an upper on a last and to pull the upper, gripper-closing mechanisms associated respectively with the different grippers 35 for closing them to grip the upper, a member common to said different mechanisms and movable to cause them to close the grippers, and means operative in response to resistance of one of said mechanisms to the movement of said member to 40 prevent the member from acting on the mechanism associated with another gripper until after it has acted on said first-named mechanism to cause the gripper controlled thereby to close.

30. In a machine for shaping uppers over lasts, 45 grippers arranged respectively to grip different portions of the margin of an upper on a last and to pull the upper, gripper-closing mechanisms associated respectively with the different grippers for closing them to grip the upper, a member common to said different mechanisms and movable to cause them to close the grippers, and a device 50 for transmitting movement from said member to one of said mechanisms, said device comprising parts relatively displaceable in response to resistance of another of said mechanisms to the movement of said member to prevent the member from acting on said first-named mechanism until after the gripper controlled by the other mechanism has been closed and the 55 member has been returned toward starting position.

31. In a machine for shaping uppers over lasts, grippers arranged to grip the margin of an upper at opposite sides of a last, said grippers being arranged to extend generally widthwise of the last and having upper-gripping jaws at their inner ends, means for effecting relative bodily movement of said grippers and the last in a direction heightwise of the last to cause the grippers 65 to pull the upper, the grippers being so mounted as to permit them to swing in directions heightwise of the last, levers also mounted for swinging movements in directions heightwise of the last and arranged to control the swinging of the grippers, and spring means controlling 70 the grippers, and spring means controlling 75 of the grippers, and spring means controlling

said levers and yieldable in response to pull of the upper on the grippers in the upper-pulling operation.

32. In a machine for shaping uppers over lasts, grippers arranged to grip the margin of an upper at opposite sides of a last, said grippers being arranged to extend generally widthwise of the last and having upper-gripping jaws at their inner ends, means for effecting relative bodily movement of said grippers and the last in a direction heightwise of the last to cause the grippers to pull the upper, the grippers being so mounted as to permit them to swing in directions heightwise of the last, levers also mounted for swinging movements in directions heightwise of the last and arranged to support the grippers at their inner end portions, the grippers being movable widthwise of the last relatively to said levers, and spring means controlling said levers and yieldable in response to pull of the upper 20 on the grippers in the upper-pulling operation.

33. In a machine for shaping uppers over lasts, grippers arranged to grip the margin of an upper at opposite sides of a last, said grippers being arranged to extend generally widthwise of the last and having upper-gripping jaws at their inner ends, means for effecting relative bodily movement of said grippers and the last in a direction heightwise of the last to cause the grippers to pull the upper, the grippers being so mounted as to permit them to swing in directions heightwise of the last, levers also mounted to swing in directions heightwise of the last and arranged to control the swinging of the grippers, springs tending to swing said levers each in one direction and yieldable in response to pull of the upper on the grippers in the upper-pulling operation, and means for adjustably limiting the movements of said levers under the influence of the springs and for thereby variably determining the normal positions of the upper-gripping jaws heightwise of the last.

34. In a machine for shaping uppers over lasts, grippers arranged to grip the margin of an upper at opposite sides of a last, said grippers being arranged to extend generally widthwise of the last and having upper-gripping jaws at their inner ends, means for effecting relative bodily movement of said grippers and the last in a direction heightwise of the last to cause the grippers to pull the upper, means supporting said grippers at their outer end portions for swinging movements in directions heightwise of the last, levers mounted for swinging movements in directions heightwise of the last and arranged to support the grippers at their inner end portions, and springs tending to swing said levers each in one direction and yieldable in response to pull of the upper on the grippers in the upper-pulling operation.

35. In a machine for shaping uppers over lasts, grippers arranged to grip the margin of an upper at opposite sides of a last, said grippers being mounted for movements from initial retracted positions to upper-gripping positions, means for limiting said movements of the grippers, a member common to said different grippers, and means for moving the grippers from their initial positions to the positions determined by said limiting means by movement of said member and for thereafter closing the grippers on the margin of the upper by further movement of said member.

36. In a machine for shaping uppers over lasts, grippers arranged to grip the margin of an upper

per at opposite sides of a last, said grippers being arranged to extend generally widthwise of the last and having upper-gripping jaws at their inner ends, the grippers being also mounted for inward movements widthwise of the last to carry the jaws from initial retracted positions to upper-gripping positions, means for limiting said movements of the grippers, a member movable by the operator and common to said different grippers, and means for moving the grippers inwardly from their initial positions to the positions determined by said limiting means by movement of said member and for thereafter effecting relative closing movements of their jaws by further movement of said member.

37. In a machine for shaping uppers over lasts, grippers arranged to grip the margin of an upper at opposite sides of a last, said grippers each having a pair of upper-gripping jaws and being mounted for movements widthwise of the last to carry the jaws from initial retracted positions to upper-gripping positions, means for limiting said movements of the grippers, a member movable by the operator and common to said different grippers, means for moving the grippers from their initial positions to the positions determined by said limiting means by movement of said member and for thereafter effecting relative closing movements of their jaws by further movement of said member, springs tending to open the jaws and to return the grippers to their initial positions, and devices associated respectively with the different grippers for locking them in their upper-gripping positions with the jaws closed.

38. In a machine for shaping uppers over lasts, the combination with means for supporting a last with an upper thereon, of upper-pulling means comprising jaw-carrying members arranged to extend generally widthwise of the last at the opposite sides thereof and each having a pair of upper-gripping jaws at its inner end, said members being mounted for inward movements widthwise of the last to carry the jaws from initial retracted positions to upper-gripping positions, means for limiting the inward movements of said members, operating members associated respectively with said jaw-carrying members, and means for first moving the jaw-carrying members inwardly by movements of said operating members and for thereafter effecting relative closing movements of the jaws by further movements of said operating members while the jaw-carrying members are at the limits of their inward movements.

39. In a machine for shaping uppers over lasts, the combination with means for supporting a last with an upper thereon, of upper-pulling means comprising jaw-carrying members arranged to extend generally widthwise of the last at the opposite sides thereof and each having a pair of upper-gripping jaws at its inner end, said members being mounted for inward movements widthwise of the last to carry the jaws from initial retracted positions to upper-gripping positions, means for limiting the inward movements of said members, operating members associated respectively with said jaw-carrying members, means for first moving the jaw-carrying members inwardly by movements of said operating members and for thereafter effecting relative closing movements of the jaws by further movements of said operating members while the jaw-carrying members are at the limits of their inward movements, springs against the resistance

of which the operating members are thus movable, and devices for locking the operating members to hold the jaw-carrying members at the limits of their inward movements with the jaws closed.

40. In a machine for shaping uppers over lasts, the combination with means for supporting a last with an upper thereon, of upper-pulling means comprising jaw-carrying members arranged to extend generally widthwise of the last at the opposite sides thereof and each having a pair of upper-gripping jaws at its inner end, said members being mounted for inward movements widthwise of the last to carry the jaws from initial retracted positions to upper-gripping positions, means for limiting the inward movements of said members, crank members associated respectively with said jaw-carrying members and mounted for swinging movements in directions widthwise of the last, and means for first moving the jaw-carrying members inwardly by movements of said crank members and for thereafter effecting relative closing movements of the jaws by further movements of the crank members while the jaw-carrying members are at the limits of their inward movements.

41. In a machine for shaping uppers over lasts, the combination with means for supporting a last with an upper thereon, of upper-pulling means comprising jaw-carrying members arranged to extend generally widthwise of the last at the opposite sides thereof and each having a pair of upper-gripping jaws at its inner end, said members being mounted for inward movements widthwise of the last to carry the jaws from initial retracted positions to upper-gripping positions, means for limiting the inward movements of said members, operating members associated respectively with said jaw-carrying members, jaw-closing rods movable inwardly by said operating members, and springs for transmitting force from said rods to the jaw-carrying members to move said members inwardly prior to the closing of the jaws, said springs being yieldable to permit the closing of the jaws thereafter by further movements of the rods.

42. In a machine for shaping uppers over lasts, the combination with means for supporting a last with an upper thereon, of upper-pulling means comprising jaw-carrying members arranged to extend generally widthwise of the last at the opposite sides thereof and each having a pair of upper-gripping jaws at its inner end, said members being mounted for inward movements widthwise of the last to carry the jaws from initial retracted positions to upper-gripping positions, means for limiting the inward movements of said members, crank members associated respectively with said jaw-carrying members and mounted for swinging movements in directions widthwise of the last, jaw-closing rods movable inwardly by said crank members, springs through which the rods are thus operated by the crank members, and other springs arranged to move the jaw-carrying members inwardly by the movements of the rods and yieldable thereafter to permit the closing of the jaws by further movements of the rods.

43. In a machine for shaping uppers over lasts, the combination with means for positioning a last with an upper thereon, of upper-pulling means comprising a gripper arranged to extend generally in a direction other than heightwise of the last and having a pair of upper-gripping jaws at one end thereof, means providing a fulcrum

for said gripper about which it may swing in directions heightwise of the last, and a spring-controlled lever mounted to swing in directions heightwise of the last and arranged to control the swinging of the gripper, said lever being yieldingly movable in response to resistance of the upper to the pull applied thereto by the gripper in the upper-pulling operation.

44. In a machine for shaping uppers over lasts, the combination with means for positioning a last with an upper thereon, of upper-pulling means comprising a gripper arranged to extend generally in a direction other than heightwise of the last and having a pair of upper-gripping jaws at one end thereof, means supporting said gripper in a location comparatively remote from its jaws for swinging movements in directions heightwise of the last, a lever mounted to swing in directions heightwise of the last and supporting the gripper in a location nearer the jaws, and a spring controlling said lever and yieldable in response to resistance of the upper to the pull applied thereto by the gripper in the upper-pulling operation.

45. In a machine for shaping uppers over lasts, the combination with means for positioning a last with an upper thereon, of upper-pulling means comprising a jaw-carrying member having a pair of upper-gripping jaws thereon, said member being mounted for movement to carry the jaws bodily from an initial retracted position to upper-gripping position, means for limiting said movement of the jaw-carrying member, a jaw-closing member movable relatively to said jaw-carrying member to effect relative closing movement of the jaws, and means for imparting said movement to the jaw-carrying member by movement of the jaw-closing member in jaw-closing direction prior to the closing of the jaws.

46. In a machine for shaping uppers over lasts, the combination with means for positioning a last with an upper thereon, of upper-pulling means comprising a jaw-carrying member having a pair of upper-gripping jaws thereon, said member being mounted for movement to carry the jaws bodily from an initial retracted position to upper-gripping position, means for limiting said movement of the jaw-carrying member, a jaw-closing member movable relatively to said jaw-carrying member to effect relative closing movement of the jaws, a crank member for operating the jaw-closing member, means for imparting said movement to the jaw-carrying member by movement of the jaw-closing member in jaw-closing direction prior to the closing of the jaws, and a device for locking said crank member to hold the jaw-carrying member at the limit of its movement with the jaws closed.

47. In a machine for shaping uppers over lasts, the combination with means for positioning a last with an upper thereon, of upper-pulling means comprising a jaw-carrying member having a pair of upper-gripping jaws thereon, said member being mounted for movement to carry the jaws bodily from an initial retracted position to upper-gripping position, means for limiting said movement of the jaw-carrying member, a jaw-closing rod movable relatively to said jaw-carrying member to effect relative closing movement of the jaws, a spring on said rod for imparting said movement to the jaw-carrying member by movement of the rod in jaw-closing direction prior to the closing of the jaws, another spring on said rod, and means for operating the rod through said other spring.

BERNHARDT JORGENSEN.
